CLAIM

The ornamental design for a television monitor, as shown and described.

DESCRIPTION

FIG. 1 is a perspective view of a television monitor showing my new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof; and,

FIG. 7 is a rear elevational view thereof.

FIG. 8 is a perspective view of a second embodiment of a television monitor;

FIG. 9 is a top plan view thereof;

FIG. 10 is a left side elevational view thereof;

FIG. 11 is a front elevational view thereof;

FIG. 12 is a bottom plan view thereof;

FIG. 13 is a right side elevational view thereof; and,

FIG. 14 is a rear elevational view thereof; and,

FIG. 15 is a perspective view thereof; similar to FIG. 8 shown in its environmental use; the broken line showing of the human figure is for illustrative purpose only and forms no part of the claimed design.
